KNITTED PILE FABRICS

John L. Hubbard, Cornwall, N.Y., assignor to The Firth Carpet Company, Inc., New York, N.Y., a corporation of New York

Original application July 25, 1957, Ser. No. 674,142, now Patent No. 2,971,359, dated Feb. 14, 1961. Divided and this application May 23, 1960, Ser. No. 30,997

5 Claims. (Cl. 66—191)

This invention relates to knitted pile fabrics wherein the pile yarn is held by diagonal warps.

In most knitted pile fabrics, especially those pile fabrics made on a flat bed knitting machine, the pile is created either as a warp stitch with extended loop, or as a pile loop held between two adjacent warp stitches wherein the ends of the loop are tied into the bight of both warp stitches, or as an individual thread going up and down above backing wefts.

The novelty of the construction described herein lies in the fact that the pile tufts are held by the diagonal warp yarn extending back and forth between adjacent warp rows in successive courses. The method of making such a fabric is explained in my co-pending application Serial No. 674,142, filed July 25, 1957, now Patent No. 2,971,359.

It is an object of this invention to provide a knitted pile fabric wherein pile tufts are formed below the warp ends of the knitted fabric and above the backing wefts of said fabric.

It is another object of this invention to provide a knitted pile fabric having a warp knitted tricot base with backing wefts being laid through the bights of the warp stitches of the tricot base and pile tufts held between adjacent warp stitch rows by warp ends crossing diagonally from one warp row to the next warp row in the next succeeding course.

It is yet another object to provide a knitted pile fabric as above wherein a sizing is applied to the base.

These and other objects will be better understood by reference to the following detailed description and drawings, showing, by way of example, a preferred embodiment of this invention, and wherein:

FIGURE 1 is a diagrammatic enlarged view of the fabric construction of this invention; and

FIGURE 2 is a diagrammatic enlarged view of the fabric construction without the inserted pile face yarns.

Referring to FIGURE 2, which is a generally known flat construction without pile, the figure comprises courses 1—5 with warp rows of stitches 6—9 made up of warp yarns 10—14. As may be seen from this figure, the base construction is not novel in itself in that bights of stitches are formed by adjacent needles, which is common in flat knitting. However, instead of merely having a knitted fabric of the warp tricot type, backing weft threads 30, 31 and 32 extend back and forth in successive courses over at least three warp rows and are held within the fabric by the bights of the adjacent warp stitches. More specifically, the backing weft thread 30 goes over the warp stitches in warp rows 6, 7 and 8 in Course 1 and returns, in Course 2, back over the warp stitches in warp rows 8, 7 and 6. Backing weft thread 33, starting in Course 1, crosses warp rows 7, 8 and 9 in that Course and returns to warp row 7 in Course 2 going back through the bights of stitches in rows 9 and 8 also.

This construction of backing wefts has a multiple purpose when used in a pile fabric as outlined in this invention. As is well-known to those familiar with the art of knitting, the warp tricot knit by itself is subject to considerable shrinkage, particularly in course materials where a gauge of 12 or less is being used. It has been found that

2

the lower the gauge number is the more, percentage-wise, the amount of shrinkage of such a warp tricot knit construction will be. If a turf is inserted around the warp thread 11 for instance, without having backing wefts 30, 31 and 32 crossing underneath this warp thread, the tuft would fall out since there is nothing beneath it to prevent it from doing so. Furthermore, if a pile fabric as coarse as those used in the upholstery and floor covering fields is made, a shrinkage such as is common in a tricot weave would be most unsatisfactory because the coarse yarns used would not merely be shrunk by virtue of the back and forth crossing warp ends, but would also tangle and make the end product unstable. Therefore, the backing threads which are laid in, back and forth across three chain stitches, not only provide the pile tufts with a backing which holds them in place, but also serve to keep the fabric from excessive shrinkage. It has been found that this is particularly true if materials for the backing weft are used which have a minimum amount of stretchability or elasticity. In the case of upholstery it was found that, even though cotton is a satisfactory product, fine linen, ramie or similar materials give a maximum prevention of shrinkage in the width of the fabric. In the case of floor covering it has been found that the use of jute, which is the primary 15 backing material for floor coverings in the woven field, gives the least amount of shrinkage widthwise and aids considerably in stabilizing the fabric of this invention.

It should be noted that the backing wefts cross three warp rows of stitches; this does not have to be the case. It 20 is merely an indication to show that three backing wefts can be laid in within the same course just as easily as one. If only two backing wefts are desired within one course the threading of the backing wefts can be the same as described, one for each warp end, but instead of shifting 25 backing weft 30, for instance, across three warp rows of stitches 6, 7 and 8 within the same course, it will only be laid in between two warp rows of stitches, 6 and 7 for instance. If this is followed through with only the backing wefts, only two of them will be next to each other in the same course. In other words, if there are as many backing wefts as there are warp ends then the number of backing wefts within one course depends on how many warp rows of stitches these backing wefts are laid across within the same course.

45 Referring to FIGURE 1, the pile tufts may be inserted in various ways so that each is positioned around and beneath a warp thread which crosses diagonally from a warp stitch in a given course and warp row to the warp stitch in the next adjacent warp row in the next course. 50 As shown in FIGURE 1, Course 1, the U-shaped pile tuft 40 is underneath warp end 11 and above backing wefts 30, 31 and 33, thus the closed end of the U-shaped pile tuft 40 is held down by the warp end 11 which extends diagonally from the bight of the stitch formed prior to the 55 formation of the stitch in Course 1 and warp row 6 over to warp row 7, thus creating a diagonal straight and tight thread 11 holding down the pile tuft 40. Warp end 11 next travels back from warp row 7 to warp row 6 in Course 2 forming its bight within Course 2 and holding 60 down the U part of pile tuft 42 between warp rows of stitches 6 and 7. At the same time, backing wefts 33, 30 and 31 have also returned into the space between warp rows 6 and 7 in Course 2 and support the tuft 42 beneath warp end 11. This pattern of movement of the warp ends 65 is followed throughout the fabric, the pile tufts always being held down by the diagonal warp ends as they proceed diagonally from one warp row to the next adjacent warp row in the next succeeding course.

It is advantageous to have the pile tightly held in between the backing and the crossing warp threads similar to the way they are interlaced in a woven pile fabric. The drawing is exaggerated, actually the warp rows and the

courses are very close to each other as in other fabrics. Therefore, the diagonally extending warps will, in the actual fabric, have a lateral rather than a diagonal appearance. This lateral appearance will simulate a filling thread of a woven fabric and thereby the knitting construction of this invention will look much like its woven counterpart.

In order to make the fabric more substantial and more like a woven fabric it is found advantageous to size the backing of the fabric with materials similar to those with which comparable woven fabrics are sized. Starches, latexes and plastic coatings, as well as foam coatings for fabrics have been found a valuable addition to make this a satisfactory commercial product. In the case of upholstery and floor coverings the sizing not only serves as a stabilizer for the fabric itself but also creates a tuft bind by seeping slightly through the backing wefts and adhering the U part of the pile tightly to both the warp end which it crosses as well as to the backing weft above which it lies.

This application is a division of my co-pending application Serial No. 674,142, filed July 25, 1957, now Patent No. 2,971,359.

What I claim as novel and desire to secure by Letters Patent of the United States is:

1. A knitted pile fabric comprising a warp knitted tricot base, backing wefts extending back and forth in successive courses, said wefts being laid across the bights of the warp stitch loops of said tricot base, and pile tufts held down between adjacent warp stitch rows by warp ends extending diagonally from one warp row in a given course to the next adjacent warp row in the next succeeding course.

2. A knitted pile fabric comprising parallel rows of bights of warp stitch loops, said loops being formed by warp ends extending diagonally back and forth with respect to adjacent rows of bights of stitches in successive courses, backing wefts extending back and forth in suc-

cessive courses, said wefts being laid in through the bights of the warp stitches, and pile tufts held between the warp rows of stitches by the diagonal warp ends and above the laid in backing wefts.

5. A knitted pile fabric comprising parallel wales of bights of warp stitches, said warp stitches being interconnected and formed by warp ends extending back and forth through adjacent bights of stitches in adjacent wales and in successive courses, backing wefts laid across at least three wales of bights of warp stitches, said wefts extending back and forth in successive courses, and pile tufts held beneath the warp ends and above the backing wefts between adjacent wales of warp stitches and the back side of the fabric having sizing applied thereto.

15 6. A knitted pile fabric as described in claim 3 wherein all the pile yarns are U tufts thereby creating a pile surface of the velvet type.

7. A knitted pile fabric floor covering comprising a tricot type warp base with warp ends extending back and forth between adjacent wales of stitches in successive courses, backing wefts equal in number of ends to the warp ends extending back and forth over at least three wales of warp stitches in successive courses, U-shaped pile tufts equal in number to the number of stitches, said tufts 20 being held beneath the crossing warp ends between adjacent wales of warp stitches and above the backing wefts, and the backing of said floor covering being provided with a sizing which secures the warp, the backing wefts and the lower portion of the pile tufts together.
